Inventor.

Thomas, Smith, Jr.

United States Patent Office.

THOMAS SMITH, JR., OF BOSTON, MASSACHUSETTS.

Letters Patent No. 96,987, dated November 16, 1869.

IMPROVEMENT IN TOPS FOR SIRUP-PITCHERS.

The Schedule referred to in these Letters Patent and making part of the same.

To all persons to whom these presents shall come:

Be it known that I, THOMAS SMITH, Jr., of Boston, county of Suffolk, and State of Massachusetts, have invented certain new and useful Improvements in Tops of Sirup-Pitchers, &c.; and that the following is a full and exact description of the same, reference being had to the accompanying plate of drawings.

The present invention relates to sirup-pitchers more particularly, although the improvements embraced by it may be adapted to other pitchers, &c.; and

The invention consists in moulding or otherwise forming, in one and the same piece of metal or other suitable material, the top or encircling rim to the body of a pitcher, &c., and the pivot or spindle on which the cover or lid thereto is to be hung and to turn.

In the accompanying plate of drawings, my improvements in pitcher-tops, &c., are illustrated.

Figure 1 is a plan view of the top and encircling rim to a pitcher, moulded or formed according to the present invention.

Figure 2, a plan view of the lid or cover-blank, showing its "tail-piece" before it is bent or formed into a but.

Figures 3 and 4, transverse sections, in planes of lines $x\ x$, fig. 1, and $y\ y$, fig. 2, respectively.

Figure 5, a central vertical section of the top, fig. 1, and lid, fig. 2, fastened and hung together.

A, in the drawings, represents a top or rim, suitable, in the present instance, for sirup-pitchers, whereon, by its end B, it is to be placed, and secured in any proper manner.

C, the spout or nozzle to top A.

Along the side D of the top A, diametrically opposite to its spout C, is a pivot or spindle, a , moulded or otherwise formed in the recess b of the top, in one and the same piece of metal or other suitable material, of which the top proper is itself made or formed.

This pivot a terminates, at each end of the recess b , with a space, c , around it, on the lower side, from end to end.

E, a cover or lid, adapted to the top A, hereinbefore referred to.

This cover or lid E, at one end the proper end, has moulded or otherwise formed with it, and in one and the same piece of metal or other suitable material, a tail-piece, F, of proper form and size, to be bent or formed into a but about the pivot a of the top A, as shown in fig. 5, when the lid is to be attached thereto, said tail-piece, when thus bent, being secured, by soldering or otherwise, firmly to the under side of the lid.

By my invention, it is obvious that the top to a pitcher, &c., the lid, and the hinge or joint of the two, are produced by the use of only two separate and distinct pieces or parts, viz., the one the top, and the other the lid, owing to their separate formation or manufacture, the advantages of which are many, among which may be enumerated, as the more important, that the labor of manufacture is much reduced, and consequently the expense, and that a much better and more reliable and compact joint or hinge is obtained, than by the old method of manufacture, wherein a separate pin or pivot was driven and secured in the top, to produce the pintle or axis of the hinge.

It will be here remarked, that in lieu of moulding the pin within a recess of the top, bringing it below the upper edge thereof, as shown, it may be located above the same, (see Figure 6 of the drawings,) reducing the size of the lid, as is manifest from an inspection of said figure.

Having thus described my invention,

I will state my claims, as follows:

1. The construction of the encircling ring B for the body of the pitcher, with the spindle or pivot a , from one piece of metal, as shown and described.

2. In combination with the encircling ring B, as constructed, the top A, as shown and described.

The above specification of my invention signed by me, this 6th day of October, A. D. 1869.

THOMAS SMITH, JR.
